UNITED STATES PATENT OFFICE.

FRITZ STEINMANN, OF NIEDERSCHÖNEWEIDE, NEAR BERLIN, GERMANY.

VARIABLE-PRESSURE INTENSIFIER.

1,084,715.

Specification of Letters Patent.

Patented Jan. 20, 1914.

Application filed August 21, 1912. Serial No. 716,121.

To all whom it may concern:

Be it known that I, FRITZ STEINMANN, a subject of the King of Prussia, residing at Niederschönweide, near Berlin, in the 5 Kingdom of Prussia and German Empire, have invented certain new and useful Improvements in Variable-Pressure Intensifiers, of which the following is a specification.

10 My invention relates to pumps for the supply of water or other fluid under variable pressure, wherein the variation of pressure is obtained by pistons of different areas.

The novel features of my invention reside 15 in the provision of a piston having working surfaces of different areas acting to suck in water or other liquids during the return stroke of the piston, and to supply, during the forward stroke, first the liquid at a lower 20 pressure and subsequently at an increased pressure, the degree of pressure depending on one or the other of two positions of a shut-off-valve arranged in advance of the discharge pipe, such positions causing either 25 the larger area of the piston alone, or both the larger and the smaller area of the same together to act in discharging the liquid into the exhaust pipe. The said valve may be operated manually or automatically.

30 My invention is shown in the accompanying drawings wherein—

Figure 1 is a vertical section through my new pump, with the valve arranged for automatic operation, and Fig. 2 is a section 35 view of the valve shown in Fig. 1, but in the other end position.

The improved pump, according to this invention, consists of a low-pressure cylinder *a*, within which works a piston *b*, the rod *c* 40 of which carries at its upper end a piston *d* forming with the portion *c'* of the rod a kind of a stepped piston having two different active areas. The said piston *d* reciprocates within a high-pressure cylinder *e*, the 45 upper end of which is formed as a valve casing *e'* containing a valve *f*. The valve casing is connected by a supply-pipe *l* with any suitable feed-water tank or supply, not shown in the drawings, and a discharge 50 pressure-pipe *m* connected with the valve casing leads to the hydraulic engine.

If the valve *f* occupies the position shown in Fig. 2 and the piston *b* is forced upward by means of the liquid, it is obvious that the 55 highest degree of pressure will be obtained, because, only the small area of the portion

o' of the piston rod is made operative and the pressure liquid above the piston *d* not only is made to deliver its working effect directly into the hydraulic engine, but also, 60 through a side conduit *g*, below the piston *d*. In this case though but a small quantity of water under pressure will be made operative, the pressure obtained is considerable. If, now, the valve *f* is moved to the 65 position shown in Fig. 1, the full area of the piston *d* is made operative for producing the pressure and the whole quantity of water under pressure resulting therefrom is forced only through pipe *m* into the hydraulic engine, no water being forced 70 through conduit *g*. During this part of the operation, the differential area of the piston *d* will cause suction of feed-water of low pressure through the conduit *g*, and a large 75 volume of water of a comparatively low degree of pressure will thus be supplied.

The valve *f*, is arranged to be automatically shifted from one to the other position during the working stroke of piston *b*. To 80 this end the valve *f* on one side is placed under the action of a spring *h*, while, on the opposite side of said valve its casing is constructed to form a hydraulic cylinder *i*. Owing to a connecting passage *k* provided 85 in the valve casing the liquid pressure entering the hydraulic press may pass into said cylinder *i*. The operation, in this case, is as follows:—On starting the valve *f* will occupy the position shown in Fig. 1, where- 90 in, initially, the piston *d* will produce liquid pressure, while the difference in areas of the two surfaces *d* and *c'* serves to draw in the feed-water by suction from the supply-tank. Now, as soon as the liquid under pressure 95 within the hydraulic press rises to a predetermined level, which may be varied as desired, it passes through the passage *k* into the cylinder *i*, thereby actuating the valve *f* and shifting the same to the position 100 shown in Fig. 2. Now, for generating liquid pressure, only the area *c'* of the piston *d* will be operative, since the liquid pressure will act as well for working the press, as also against the differential area between the surfaces *c'* and *d* of the piston. It will be readily understood, that in this case the generation of liquid pressure is automatically controlled by the actual expenditure of working power in the hydraulic press and automatically adapts itself to the amount of power 105 temporarily required. At the time where 110

but little power is being consumed by the press, the resistance being low, the amount of liquid required to provide such pressure will be comparatively large, and at the same 5 rate as the resistance increases, the supply of the liquid medium for generating the pressure equally decreases.

What I claim is:—

1. Variable liquid pressure pump, comprising a low pressure piston, a differential auxiliary piston, an inlet port for the low pressure operating fluid, a discharge port for the fluid under high pressure, an automatic valve interposed between the said auxiliary piston and the said two ports and a conduit for leading the fluid to the rear of said auxiliary piston, said conduit being adapted to communicate either with the said inlet port or said discharge port, according to the position of the said automatic valve, and a spring acting on one side of said valve and a hydraulically operated member acting on the other side of that valve.
- 10 2. Variable liquid pressure pump, comprising a low pressure piston, a differential auxiliary piston, an inlet port for the low pressure operating fluid, a discharge port for the fluid under high pressure, an automatic valve interposed between the said auxiliary piston and the said two ports and a conduit for leading the fluid to the rear of said auxiliary piston, said conduit being adapted to communicate either with the said inlet port or said discharge port, according to the position of the said automatic valve.
- 15 20 2. Variable liquid pressure pump, comprising a low pressure piston, a differential auxiliary piston, an inlet port for the low pressure operating fluid, a discharge port for the fluid under high pressure, an automatic valve interposed between the said auxiliary piston and the said two ports and a conduit for leading the fluid to the rear of said auxiliary piston, said conduit being adapted to communicate either with the said inlet port or said discharge port, according to the position of the said automatic valve.

prising a low pressure piston, a differential auxiliary piston, an inlet port for the low pressure operating fluid, a discharge port for the fluid under high pressure, an automatic valve interposed between the said auxiliary piston and the said two ports and a conduit for leading the fluid to the rear of said auxiliary piston, said conduit being adapted to communicate either with the said inlet port or said discharge port, according to the position of the said automatic valve, and a spring acting on one side of said valve and a hydraulically operated member acting on the other side of that valve.

In testimony whereof I have affixed my signature in presence of two witnesses.

FRITZ STEINMANN.
